Des. No. 20,096

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,096, dated August 12, 1890.

Application filed June 25, 1890. Serial No. 356,720. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, and Parasol Handles; and I do hereby declare the following to be a full, clear, and exact description of the invention, such as will enable others skilled in the art to 10 to which it pertains to make and use it, reference being had to the accompanying drawing, which forms part of this specification.

My invention relates to an improvement in designs for cane, umbrella, and parasol handles; and it consists in an ornamental shape, 15 which will be more fully described hereinafter, whereby a beautiful and attractive effect is produced.

The accompanying photographic illustration represents my invention.

A represents the main portion of the handle, which has its upper end bent at an angle, as shown. Upon the main portion of the handle are formed the elongated angular projections, as shown, and which are arranged in 25 curved lines. The outer end of this handle is formed into a head B of any suitable description, the horizontal portion A' forming the neck of the said head B, and in the mouth of which is a small animal C. Coiled around 30 the handle at that point where the bend is made is a serpent G. The serpent, the small animal, and the head, in the mouth of which the small animal is held, constitute a very novel design. If so desired, the serpent may 35 be omitted without departing from the spirit of my invention.

Having thus described my invention, I claim—

A design for cane, umbrella, and parasol 40 handles, consisting of a main vertical portion and an upper horizontal portion, which forms the neck of an animal, the outer end of the horizontal portion formed into an animal's head, and a small animal held in the mouth 45 of the said head, as herein shown and described.

In testimony whereof I affix my signature in presence of two witnesses.

ALBERT ROSENSTEIN.
